UNITED STATES PATENT OFFICE.

WILLIAM ROY MORRIS, OF BOISE, IDAHO, ASSIGNOR TO THE UNIVERSAL ENGINEERING AND POWER COMPANY, OF BOISE, IDAHO, A CORPORATION OF IDAHO.

WATER-MOTOR.

1,377,719.

Specification of Letters Patent. Patented May 10, 1921.

Application filed October 12, 1920. Serial No. 416,435.

To all whom it may concern:

Be it known that I, WILLIAM R. MORRIS, a citizen of the United States, residing at Boise, in the county of Ada and State of Idaho, have invented certain new and useful Improvements in Water-Motors, of which the following is a specification.

This invention relates to improvements in water motors and the principal object of the invention is to provide mechanism which may be placed in a flowing stream and take advantage of the current of the water for the purpose of generating power.

The primary object of the invention is to furnish the water motor with impeller blades which are so constructed and arranged as to obtain maximum power from the flowing stream with a minimum of friction.

Another object of the invention is to provide improved mechanism for transmitting the power obtained by the impellers to any suitable place where said power is to be utilized.

A still further object is to furnish a water motor with improved means for raising and lowering the impeller shafts so that the impellers may be placed in the most advantageous positions to take advantage of the passing current.

Another object of the invention is to provide improved thrust bearings for taking up the thrust exerted by the impeller shafts so that said shafts may freely turn with a minimum of friction.

With the foregoing objects outlined and with other objects in view which will appear as the description proceeds, the invention consists in the novel features hereinafter described in detail, illustrated in the accompanying drawings and more particularly pointed out in the appended claims.

Referring to the drawings:

Figure 1 is a side view of my improved motor.

Fig. 2 is a top plan view of the same.

Fig. 3 is an end view.

Fig. 4 is a detail sectional view taken on the line 4—4 of Fig. 3.

Fig. 5 is a detail sectional view taken on the line 5—5 of Fig. 4.

Fig. 6 is a longitudinal sectional view of one of my improved thrust bearings.

In the drawings, 1 represents a main or stationary frame which in the present in-

stance consists of vertical posts 2; side bars 55 3; end bars 4 and brace rods 5.

The vertical posts 2 are preferably supported on stone or concrete piers 6 which are built upon the bed of the stream and each of the posts 2 is preferably formed of channel- 60 iron as shown. Mounted in the frame 1 is a vertically adjustable frame 7 having end cross bars 8 which have their ends slidably mounted in the channels of the corner posts 2 of the main frame. 65

The adjustable frame 7 is provided with a plurality of vertically disposed stationary threaded bars 9, the threaded portions of which pass through plates 10 carried by the upper bars of the stationary frame. Resting on the plates 10 are gears 11 having internal screw threads which engage the thread portions of the bars 9. The gears 11 mesh with worm gears 12 fixed to longitudinally disposed shafts 13 which are mounted at the 75 upper portion of the stationary frame. The front ends of the shafts 13 are provided with miter gears 14 which mesh with similar gears 15 fixed to the ends of cross shafts 16. The inner ends of said cross shafts are provided with miter gears 17 which are engaged by a similar gear 18 that may be driven by a handle placed on the squared portion 19 of the shaft 20 which carries said gear 18. 80

From the foregoing description it will 85 be understood that rotation of the shaft 20 causes rotation of the shafts 16—16 in opposite directions and rotation of the shafts 13 in similar directions and the worm gears 12 are so disposed as to cause movement of the gears 11 to simultaneously elevate all of the bars 9 and with it the movable frame 7. It will thus be seen that the adjustable frame may be elevated or lowered to a position most desirable for taking advantage of the current of the stream. 90

The adjustable frame is provided with a pair of parallel shafts 21 each of which has its forward end rotatably mounted in one of the cross bars of the adjustable frame 100 and its rearward end provided with one half 22 of a thrust bearing 23, the other half 24 of the thrust bearing being secured to one of the cross bars of the adjustable frame. 95

Each shaft is provided with pairs of propeller blades 25—26 and it will be noted that each blade of a propeller is of substan- 105

tially semi-circular shape and that the two blades of each propeller are arranged at substantially right angles to each other. It will also be noted that the lateral edges 27 of the blades overlap each other.

The propeller of the opposite shafts extend in opposite directions to each other. In other words, the thread or pitch formed by the propellers on one shaft is arranged 10 in a direction opposite to the thread or pitch formed by the propellers on the other shaft and in consequence the propellers on the two shafts cooperate through the medium of the water passing between the same and 15 in consequence maximum efficiency is obtained by the relative arrangement of the propellers of the two shafts.

It will be noted that the outer edges of the blades are connected together by reinforcing bars 28 which function to tie the 20 blades together and relieve the same of thrust from the water which would otherwise damage the blades unless they were made particularly heavy.

25 Each of the shafts 21 is provided with a fixed worm gear 29 and these worm gears operate gears 30 mounted upon the lower ends of shafts 31 which are carried by the adjustable frame and have miter gears 32 at their upper ends. These miter gears operate similar gears 33 fixed to a shaft 34 from which the power may be taken by any suitable means.

35 From the foregoing I believe that the construction and operation of my improved mechanism will be readily understood by those skilled in the art and I am aware that various changes may be made in the construction shown without departing from the 40 spirit of the invention as disclosed in the annexed claims.

What I claim and desire to secure by Letters-Patent is:

1. A water motor including a stationary 45 frame having corner posts provided with guiding means, a vertically adjustable frame having end members engaging said guiding means for guiding the adjustable frame vertically, and means for raising and lowering 50 said adjustable frame including a plurality

of threaded rods fixed to the adjustable frame and extending above the stationary frame, gears having internal threads engaging the threaded portions of said rods, a plurality of parallel shafts extending longitudinally of the stationary frame and provided with gears which engage the other gears, a plurality of cross shafts having gears at their outer ends, gears provided upon the ends of the longitudinally disposed 60 shafts and engaging the gears of the cross shafts, gears provided upon the inner ends of said cross shafts, a common gear for driving the last named gears, and manually operated means for driving said common gear. 65

2. A motor of the kind defined by claim 1 in which the adjustable frame is provided with a plurality of longitudinally extending propeller shafts, propellers mounted upon said shafts, and thrust bearings for 70 taking up the thrust exerted by said shafts.

3. A motor of the kind defined by claim 1 in which the adjustable frame carries a plurality of propeller shafts, series of propellers mounted upon each of said shafts, 75 and each propeller consisting of two blades, one of which is arranged substantially at right angles to the other, said blades being of substantially semicircular form and the radial edges of one blade overlapping the 80 radial edges of the other blade.

4. A motor of the kind defined by claim 1 in which the adjustable frame is provided with a plurality of shafts, series of propellers arranged upon each of said shafts, 85 each of said propellers consisting of a plurality of blades arranged at substantially right angles to each other, the blades of the propellers of the opposite shafts forming substantially screws, and the threads of one 90 screw being of a pitch opposite to that of the thread of the other screw.

5. A motor of the kind defined by claim 1 in which the adjustable frame is provided with a plurality of parallel shafts, propellers mounted upon each of said shafts, and means for transmitting power from said shafts. 95

In testimony whereof I affix my signature.
WILLIAM ROY MORRIS.

It is hereby certified that the assignee in Letters Patent No. 1,377,719, granted May 10, 1921, upon the application of William Roy Morris, of Boise, Idaho, for an improvement in "Water-Motors," was erroneously described and specified as "The Universal Engineering and Power Company," whereas said assignee should have been described and specified as *The Universal Engineering Construction and Power Company*, as shown by the records of assignments in this office; and that the said Letters Patent should be read with this correction therein that the same may conform to the record of the case in the Patent Office.

Signed and sealed this 2d day of August, A. D., 1921.

[SEAL.]

KARL FENNING,

Acting Commissioner of Patents.

Cl. 170—131.
